CHAISE LONGUE

Albert F. Kronman, Locust Valley, N. Y.

Application May 11, 1951, Serial No. 15,134

Term of patent 3½ years

(Cl. D15—11)

To all whom it may concern:

Be it known that I, Albert F. Kronman, a citizen of the United States of America, residing in Locust Valley, county of Nassau, New York, have invented a new, original, and ornamental Design for a Chaise Longue, of which the following is a specification, reference being had to the accompanying drawing, forming a part hereof.

In the drawing:

I claim:

The ornamental design for a chaise longue, substantially as shown.

ALBERT F. KRONMAN.
